CASKET CONSTRUCTION

David Oppenheim, Detroit, Mich.

Application July 8, 1937, Serial No. 152,599

5 Claims. (Cl. 27—35)

This invention relates to caskets and more particularly to caskets which consist of an ornamental outer shell forming a shroud for an inner burial box, said shell being used repeatedly as a decorative cover for the relatively inexpensive burial boxes.

Since the purchase of an ornamental casket is an item of relatively large expense, it is one of the objects of the present invention to provide a casket construction whereby the cost of funerals may be greatly decreased without sacrificing the beauty of an expensive casket construction.

Another object of the invention is to provide a two-piece casket in which there is provided improved means for connecting the shroud and the inner burial box, said means permitting easy and convenient disconnecting and lowering of the burial box into the grave.

It is an additional object of the invention to provide a casket of the foregoing character which is simple in construction and is relatively inexpensive to manufacture, and in which the box suspending or connecting means are simple and dependable in operation.

Other objects of this invention will appear in the following description and appended claims, reference being had to the accompanying drawing forming a part of this specification wherein like reference characters designate corresponding parts in the several views.

Fig. 1 is a perspective view of the casket in its assembled position, the cover being partly opened to show the interior thereof.

Fig. 2 is a longitudinal vertical sectional view of the casket, showing the suspension means.

Fig. 3 is a sectional view illustrating the method of lowering the burial box into the concrete vault.

Before explaining in detail the present invention it is to be understood that the invention is not limited in its application to the details of construction and arrangement of parts illustrated in the accompanying drawing, since the invention is capable of other embodiments and 45 of being practiced or carried out in various ways. Also it is to be understood that the phraseology or terminology employed herein is for the purpose of description and not of limitation, and it is not intended to limit the invention claimed 50 herein beyond the requirements of the prior art.

In the drawing there is shown by way of example a casket construction embodying the present invention. Referring to the drawing, the same comprises generally an ornamental outer shell or shroud 10 having the general appear-

ance of an ordinary casket without a bottom, a burial box 11, and suspension means generally indicated by the numeral 12 by which the burial box 11 is operatively suspended in the shell 10 and can be lowered therefrom onto the straps 13 for lowering into the concrete vault 14. Thus, the burial box 11 is actually buried in the concrete vault 14, while the ornamental shell 10 which is relatively expensive is preserved for repeated use.

The cover of the shell 10 comprises a fixed part 15 and a hinged part 16 which can be opened to permit display of the remains of the deceased. Handles 17 are provided on the shell as shown for the purpose of convenient carrying and handling of the shell and burial box as a unitary casket. The suspension means are provided at each of the ends of the shell and connect with the ends of the burial box to form the casket. The mechanism provided at the respective ends 15 of the casket are in effect complementary clamps which are substantially similar in construction. Each of said mechanisms comprises a bracket 18 secured to the shell 10, and a bolt 19 supported by the bracket 18, the bolt 19 passing 20 through the hole provided in the bracket. A nut 20 operatively engages the bolt 19 and is prevented from rotation by a guide pin 21 provided on the bracket 18. Thus, rotation of the bolt 19 may be effected by means of a wrench 22 adapted to pass through small concealed holes 23 provided in the cover of the shell 10, the wrench 22 engaging the square heads 24 of the bolts which upon turning causes vertical movement of the nut 20.

The burial box 11 is provided with two loop brackets or eyes 25 which are engaged by the hook portions of the hook rods 26, two of such hook rods being provided at each end of the casket, said rods being hinged at the nut 20 as 40 indicated at 27.

The actual process of disconnecting the shell and the burial box and burying the burial box is illustrated in Fig. 3. Referring thereto, 28 indicates the grave pit at the bottom of which 45 there is provided a concrete or other suitable vault 14 for receiving the burial box. The casket is placed on the frame 30 which provides a firm footing therefor and which prevents caving in of the edges of the pit. The lowering straps 50 13 are of any desired conventional construction and may be secured in and operated by the drums 31 provided with suitable spring mechanisms (not shown) to produce the desired tension on the straps to enable gradual lowering of the burial 55

box 11 into the vault 29. It should be noted that the sliding cover 32 of the box is moved from under the fixed top part 33 for closing the box 11 before the hinged cover 16 is closed. 5 It is also important to note that when the box 11 is suspended in the shell 10, it may be raised by the bolts against the stops 34 secured to the shell 10, and therefore it is held in the shell very tight and secure. 10 It is an important feature of the present invention that with the aid of my improved suspension means lowering of the burial box onto the straps is effected gradually and with full control of the speed and distance of separation of 15 the parts. Thus the present invention permits a gradual lowering of the burial box until it rests evenly and securely on the straps of the lowering device. This disengagement of the burial box is effected without any sudden release of the 20 parts causing an uneven impact resulting in overstressing the lower strap at either end of the casket which causes tilting of the burial box, or possible breakage of the straps. 25 From an examination of Figs. 2 and 3 it can be seen that as the bolts 19 are rotated, preferably by means of two wrenches from both sides of the casket simultaneously, the burial box is lowered onto the straps and tension is put on 30 said straps until they fully support the burial box. Further rotation of the bolts will move the hook portions of the rods 26 downward with respect to the loop brackets 25. Since the hook rods 26 in their engaged position are disposed at an angle, as soon as their hook portions clear 35 the loop brackets 25, the rods swing away from from the brackets and the burial box may be lowered without interference from said rods. Construction and operation of the lowering straps and their drums is well known in the art 40 and therefore need not be described in detail as the features of such devices do not comprise a part of the present invention. 45

Thus, the present invention provides an improved means whereby suspension of the burial box in the outer decorative shell is made dependable and secure, and the lowering of said box onto the strap may be effected gradually and positively controlled at all times during the disconnecting of the burial box from the shroud. 50

I claim:

1. In a casket construction having an outer decorative shell and an inner burial box, means detachably connecting said shell and said box, said means comprising a plurality of vertically arranged bolts carried by said shell and a corresponding plurality of travelling nuts engaging said bolts, means preventing rotation of the nuts when the respective bolts are rotated, and rigid hook rods connected with said nuts and depending therefrom for suspending and lowering said burial box, said hook rods being hooked into loops upon the said burial box and automatically

disengageable therefrom after the burial box is supported by lowering straps. 5

2. In a casket construction having an outer decorative shell and an inner burial box, means operatively connecting said shell and said box, said means comprising a plurality of vertically arranged bolts carried by said shell and a corresponding plurality of travelling nuts engaging said bolts, guides preventing rotation of said nuts when their respective bolts are rotated, brackets on said burial box, and hook rods carried by said nuts and fitting about said brackets at their inner, outer, and lower surfaces to detachably secure the burial box to the shell. 10

3. In a casket construction having an outer decorative shell and an inner burial box, means concealed in said shell and operable from the outside thereof for detachably connecting said shell and said box and comprising a plurality of vertically arranged bolts carried by said shell and a corresponding plurality of travelling nuts engaging said bolts and detachably supporting said burial box through swingable but rigid connecting links hooked within eye portions thereof, and means for rotating said bolts to effect a gradual lowering of the burial box relative to the shell before disconnection of the burial box from the shell takes place as a result of the lowering of the links relative to the eye portions. 15 20 25

4. In a casket construction having an outer decorative shell and an inner burial box, means concealed in said shell and operable from the outside thereof for detachably connecting said shell and said box, said means comprising a plurality of vertically arranged bolts carried by said shell and a corresponding plurality of travelling nuts engaging said bolts, guides preventing rotation of said nuts when their respective bolts are rotated, brackets on said burial box, and hook rods carried by said nuts and engaging said brackets to detachably support the burial box in the shell. 30 35 40

5. In a casket construction having an outer decorative shell and an inner burial box, means provided at each end of the casket for operatively connecting said shell and said box, said means being concealed in said shell but operable from the outside thereof and comprising a bracket secured to said shell; a vertically disposed bolt supported by said bracket; a guide pin on said bracket; a travelling nut operatively engaging said bolt and said pin, whereby rotation of the bolt causes vertical movement of said nut; loop brackets on said burial box; and hook rods secured to said nut and depending therefrom to engage said loop brackets for supporting the burial box and connecting the box and the shell to form a unitary casket structure, and means for rotating the said bolt to lower the burial box relative to the shell whereby the box may be lowered onto lowering straps prior to disengagement of the hook rods from the loop brackets. 45 50 55 60
